UNITED STATES PATENT OFFICE.

JOSÉ LLAVINA ALEMANY, OF SAN GERMAN, PORTO RICO.

APPARATUS FOR PROTECTING SHIPS AGAINST TORPEDO ATTACKS.

1,260,121.

Specification of Letters Patent. Patented Mar. 19, 1918.

Application filed July 6, 1917. Serial No. 178,916.

To all whom it may concern:

Be it known that I, JOSÉ LLAVINA ALEMANY, a subject of the King of Spain, and a resident of San German, Porto Rico, have invented a new and Improved Apparatus for Protecting Ships Against Torpedo Attacks, of which the following is a full, clear, and exact description.

Among the principal objects which the present invention has in view are: To avoid retarding the headway of a ship when provided with an apparatus of the character mentioned; to dispose said apparatus rapidly in service relation; to accommodate the docking facilities afforded ships in harbors; and to manufacture the apparatus at a reduced cost.

Drawings.

Figure 1 is a plan view of an apparatus of the character mentioned, constructed and arranged in accordance with the present invention, showing in conjunction therewith, the ship to which it is applied;

Fig. 2 is a side view of the same; Fig. 3 is a cross section of the same, the section being taken as on the line 3-3 in Fig. 1;

Fig. 4 is an enlarged detail view in section, showing the apparatus by full and dotted lines in its active and inactive positions, respectively;

Fig. 5 is an enlarged detail, showing by a top plan view a suspension boom and means for operating the same;

Fig. 6 is a detail view in cross section, the section being taken as on the line 6-6 in Fig. 5;

Fig. 7 is a longitudinal section, showing the bow of the ship, the section being taken as on the line 7-7 in Fig. 1;

Fig. 8 is a vertical cross section of a fragment of a ship's hull, showing in conjunction therewith the invention and in a modified form thereof;

Fig. 9 is a detail view showing on an enlarged scale, a portion of the modified form of the protecting belt;

Fig. 10 is a detail view showing portions of the modified form of the belt in their disassociated relation.

Description.

As seen in the drawings, to embody the present invention, a ship 15 has rigidly attached thereto and just forward of the prow

thereof, a false bow 16. The bow 16 has a cut water 17, which is reinforced by a filler 18.

As shown best in Figs. 1 and 7 of the drawings, an open space 19 remains between the hull of the ship and the sides of the cut water 17.

Pivotedly attached to the cut water 17 are link plates 20. The plates 20 have pivotally attached thereto fenders 21. The fenders 21 constitute striking walls which an offensive torpedo would engage if fired at the ship provided with the fenders 21. The fenders 21 are connected with the link plates by means of pivots 22, which permits the said plates to raise and lower at the rear or in the wake of the ship as shown best in dotted lines in Fig. 2 of the drawings. The fenders 21 are constructed of thin metal sufficiently flexible to fold against the sides of the ship, and to assume the shape thereof when they are allowed to approach the ship. This is the position which the said fenders assume when inactive, and in this position they do not retard the speed of the ship.

In the active position the fenders are held away from the sides of the ship by thrust rods. The rods 23 have hook ends, the lower hook end of each rod entering a socket or eyelet 24. The rods 23 pass through sockets or eyelets 25 on the ship, and at the edge of the bulwarks thereof. In service, the rods 23 operate as braces for holding the fenders away from the sides of the ship when they are lifted or suspended by cables 26. The cables 26 are supported by pulleys 27 at the outer ends of booms 28. The cables 26 are carried inboard, and are disposed about the winches 29 and 30. The cables 26 are wrapped on the winches 29 and 30, to enter above and below the same, respectively. The winches 29 and 30 are disposed in pairs on the shafts 31. The shafts 31 are each driven by an electric motor 32 or other suitable prime mover. By means of the winches 29 and 30 and apparatus connected therewith, the depth at which the fenders 21 are disposed in active service may be regulated, or said fenders may be lifted clear of the water.

The booms 28 are slidably mounted in runways 33 and any suitable means for extending and retracting the booms 28 may be employed.

To hold the rear ends of the fenders 21

properly extended, there is provided a two-member spreader rod 34. The spreader rod 34 is jointed at the center by a turnbuckle 35, which may be operated from the stern 5 of the ship, employing therefor any suitable and convenient means. A flexible shaft with a turning crank may be employed for the purpose of releasing the turnbuckle 35 to permit the rods 34 to part and allow the 10 fenders 21 to assume their inactive position close to and in contact with the side of the ship.

In Figs. 8, 9 and 10, a modified form of 15 the fenders 21 is disclosed. The modification consists in providing a series of separable plates 36. The plates 36 are provided with hinge knuckles 37, which are joined by means of pintle bolts 38. The pintle 20 bolts 38 are permanently secured to the thrust rods 39. The rods 39 when lifted withdraw the pintle pins 38 from the knuckles 37, and allow the individual plates 36 to be lifted by the cables 22 to the deck 25 of the ship if desired to be there stowed.

Claims.

1. An apparatus as characterized comprising a plurality of thin metal walls adapted to assume the curvature of the side 30 of a ship; means for suspending said walls in spaced relation to the sides of said ship, said means embodying a plurality of hoisting devices permanently mounted on the hull of the ship, said devices employing a 35 series of booms adjustably extensible from the sides of said ship, and winches suitably related to said booms for controlling cables guided over the ends of said booms; means for rotating said winches at will; a plurality 40 of fender bars flexibly connecting said walls and the hull of the ship, said bars being adapted for elevation above the deck of the ship for permitting the approach of said walls to the sides of said ship; and spreader rods attached to and extended between the rear ends of said walls for maintaining the spaced relation thereof.

2. An apparatus as characterized comprising a plurality of thin metal walls 50 adapted to assume the curvature of the side of a ship; means for suspending said walls in a spaced relation to the sides of said

ship, said means embodying a plurality of hoisting devices permanently mounted on the hull of the ship, said devices employing 55 a series of booms adjustably extensible from the sides of said ship, and winches suitably related to said booms for controlling cables guided over the ends of said booms; means for rotating said winches at will; a plurality 60 of fender bars flexibly connecting said walls and the hull of the ship, said bars being adapted for elevation above the deck of the ship for permitting the approach of said walls to the sides of said ship; and 65 spreader rods attached to and extended between the rear ends of said walls for maintaining the spaced relation thereof, said spreader rods being formed of a plurality of members detachably connected.

3. An apparatus as characterized comprising a plurality of thin metal walls adapted to assume the curvature of the side of a ship; means for suspending said walls in spaced relation to the sides of said ship, 70 said means embodying a plurality of hoisting devices permanently mounted on the hull of the ship, said devices employing a series of booms adjustably extensible from the sides of said ship, and winches suitably 75 related to said booms for controlling cables guided over the ends of said booms; means for rotating said winches at will; a plurality of fender bars flexibly connecting said walls and the hull of the ship, said bars being adapted for elevation above the deck of the ship for permitting the approach of said walls to the sides of said ship; spreader rods attached to and extended between the rear ends of said walls for maintaining 80 the spaced relation thereof, said spreader rods being formed of a plurality of members detachably connected; and means for disconnecting said members.

4. An apparatus as characterized, comprising a plurality of flexible thin walls adapted for vertical disposition in the path of a torpedo; and means for pivotally mounting the same in advance of the prow of a ship, said means embodying pivots for 95 permitting unrestricted vertical movement of the rear ends of said thin walls.

JOSE LLAVINA ALEMANY.
